UNITED STATES PATENT OFFICE.

FREDERICK C. FRANK, OF WEISER, IDAHO.

CAR-DOOR LOCK.

1,250,838.

Specification of Letters Patent. Patented Dec. 18, 1917.

Application filed July 6, 1917. Serial No. 178,925.

To all whom it may concern:

Be it known that I, FREDERICK C. FRANK, a citizen of the United States, and resident of Weiser, in the county of Washington and State of Idaho, have invented a new and Improved Car-Door Lock, of which the following is a full, clear, and exact description.

This invention relates to dumping cars or carts and has particular reference to that type of such devices in which the body is tiltable around a horizontal axis for dumping of the contents thereof by gravity, the material to be dumped being normally held in the body by means of a door hung upon a horizontal axis at or adjacent to the upper portion of the car body. By the term "car" as used herein I desire therefore to be understood as covering any vehicle for the conveyance and dumping of loose bulk material. This present improvement furthermore has nothing particularly to do with the means of effecting the tilting of the body for dumping purposes, nor locking means to normally prevent such tilting movement, such features being well known and of a conventional nature.

Among the special objects of this improvement is to provide a substantially automatic means for locking the door closed and holding it in such position while the car body is held in normal carrying or transporting position, but being so designed that when the body is tilted the lock will be automatically released by reason of the movement of the body into tilted or inclined position with respect to the base to which the body is pivoted and upon which the body is normally supported in transporting position.

A further object of the invention is to provide a locking means for the swinging or pivoted door so designed that the door will not only be unlocked when the body is tilted but will be given a positive impulse toward its open position to prevent the possible sticking thereof.

A still further object is to provide a locking means for a car body door which will not only be operated automatically to engage and hold the door when the body is swung down into normal or horizontal position, but will positively cause the door to be closed snugly.

With the foregoing and other objects in view the invention consists in the arrange-

ment and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which

Fig. 1 is a side elevation of a car equipped with my improvement, the door being held closed by my improved lock.

Fig. 2 is a rear elevation of the same; and

Fig. 3 is a side elevation of the car in dumping position and showing the locking device in a relatively different position with respect to the body from that of Figs. 1 and 2.

Referring now more particularly to the drawings I show a car comprising wheels 10, a frame or base 11 supported thereon for movement as usual along a track or roadway represented by the rails 12, and a body 13 supported normally upon the base 11 and held from relative movement with respect thereto by a fastener 14. As is customary in cars of this type the body is connected to the base for tilting movement around a transverse horizontal pivot 15 at the rear end of the base, the pivot being approximately midway between the transverse center of the bottom of the body and the rear end thereof.

The door 16 adapted to close the rear and otherwise open end of the body 13 is hinged to the upper rear portion of the body at 17, the axis of this hinge being parallel to the pivot 15. The vertical plane, however, of the pivot 17 is spaced to the rear of the corresponding plane of the pivot 15. The door carries a pair of lugs 18 which lie in alignment with each other and which for convenience may be the ends of the same bar 19 secured upon the outer face of the door 16 and at any convenient elevation between the upper and lower edges of the door.

Cooperating with each lug 18 is a locking member 20 pivoted upon a stud 21 and comprising at least three distinct features as follows: An upwardly projecting arm 22, an outwardly and downwardly projecting hook 23, and a downwardly and rearwardly extending cam 24, there being provided a space between the hook and the cam to accommodate and receive a lug 18. The stud 21 is carried upon the car body adjacent to

the rear end thereof and slightly above the axis of the lug 18. A bar 25 is pivotally connected at its front end 26 to the relatively stationary base portion of the car and 5 at its rear end at 27 to the upper end of the arm 22, the bar being inclined downwardly from the rear toward its front end. In the normal closed position of the door or when the car body is horizontal the lines 10 from the pivots 26 and 27 intersecting in the axis of the stud 21 form an obtuse angle, and the arrangement is such with respect to the pivot 15 that when the body is tilted and the stud 21 is carried by the body downwardly toward the line passing through the pivots 26 and 15 the angle between the bar 25 and the arm 22 will enlarge and the angle above referred to between the lines from the pivots 26 and 27 intersecting in the axis of 15 the stud 21 will be reduced and approach a right angle. In other words, when the body is swung in either direction around the pivot 15 the bar 25, being pivoted to a fixed pivot 26 at its front end, and connected at 20 its upper end to the upper end of the arm 22, will cause the locking device 20 to oscillate positively around the axis of the stud 21. It follows therefore that when the body is tilted upwardly in front and downwardly 25 at the rear the hook 23 will be lifted out of engagement with the lug 18. Since this hook portion of the locking device is located below the axis of the stud 21 and swings in an arc of a circle upward relatively to the 30 end of the body, the cam portion 24 will have a positive outward bearing action upon the lug 18 to initiate the open swinging movement of the door in the event that it should happen to stick. Fig. 3 shows how 35 this cam portion is caused to swing rearwardly with respect to the car body. After the contents of the body are dumped and the body is lowered again into normal position the door will swing naturally by gravity toward its closed position, the final closing action being effected by positive engagement of the point of the hook over the lug 18 while the hook is being swung downwardly and forwardly through the action 40 of the rigid bar 25. While this specific description of the locking device is largely in the singular, it will be understood that for best results I propose to employ one of 45 them on each side of the car body, but the 50 operation of both is the same.

The device is very simple of construction, positive in its action and cannot fail to operate automatically in both its opening and

closing movements coincidentally with the 60 tilting of the car body, and being automatic in its action requires no attention on the part of the operator.

I claim:

1. The combination with a car body having a hinged door and a relatively stationary base upon which the car body is pivoted, of a locking device carried upon the body adjacent to the door and cooperating with the door to hold the same closed when the body is in horizontal position, and means extending between the base and said locking device insuring to automatically release the locking device and positively open the door when the car body is tilted.

2. The combination with a car body having a door and a relatively stationary base upon which the body is pivoted, of a locking device carried by the car body and having detachable engagement with the door, and means connected to the base and to the locking device and serving when the body is tilted to release the door and impart to the door a positive impulse toward opening movement.

3. In a dumping car, the combination of a base, a body pivoted on a horizontal axis at the rear end of the base, said body having a door hinged at the rear end of the body and adapted to swing at its lower edge toward and from the body, said door having a laterally projecting lug, an oscillating locking member pivoted to the rear end of the body for movement around an axis above said lug, said locking member having an upwardly projecting arm and a rearwardly and downwardly projecting hook cooperating with said lug, and a rigid bar pivoted at one end to the upper end of said arm and at its other end to the base in front of the pivot between the body and the base.

4. The combination with a tiltable car body and a door hinged thereto at its upper edge for opening movement when the body is tilted, said door having a laterally projecting lug, of a locking device pivoted to the car body and having a hook engaging rearwardly and downwardly over said lug to hold the door closed, said locking device having a cam portion acting on the front side of the lug and serving to positively move the same rearwardly when the body is tilted, and means acting upon the locking device automatically when the body is tilted to cause it to rotate upon the body.

FREDERICK C. FRANK.
